UNITED STATES PATENT OFFICE.

FRED. W. GORDON, OF PHILADELPHIA, PENNSYLVANIA, ASSIGNOR TO
GORDON, STROBEL & LAUREAU, OF SAME PLACE.

CONVERTER.

SPECIFICATION forming part of Letters Patent No. 361,624, dated April 19, 1887.

Application filed May 22, 1885. Serial No. 166,346. (No model.)

To all whom it may concern:

Be it known that I, FRED. W. GORDON, of Philadelphia, Philadelphia county, Pennsylvania, have invented certain new and useful 5 Improvements in the Construction and Arrangement of Tuyeres, of which the following is a specification.

This invention pertains to the construction and arrangement of tuyeres devised, primarily, 10 for use in connection with converters employed in the manufacture of steel.

The improvements have been illustrated, and will be described, in connection with converters, for the purpose of exhibiting an adaptation 15 of the improvements.

The term "vessel," often occurring in this specification, has reference to a converting-vessel, or other vessel adapted for metallurgical operations in connection with my improvements. 20

My improvements will be readily understood from the following description, taken in connection with the accompanying drawings, in which—

25 Figure 1 is a side view, part in elevation and part in vertical section, of a converter provided with tuyeres exemplifying my improvements; Fig. 2, a longitudinal vertical section of a tuyere and its operating mechanism; Fig. 3, 30 a combined plan and horizontal section at one of the tuyere-trunnions upon line y, and Fig. 4 a side view of a tuyere-shank.

In the drawings, A indicates a converting-vessel, shown as of the fixed or non-tipping 35 type; B, outwardly-inclined tuyere-ports in the wall of the vessel; C, a margin-plate at each port, firmly secured to the outer wall of the vessel and provided with a beveled seat at its circular central opening; D, a bustle-pipe 40 encircling the vessel below the ports and formed in separate segments, each segment reaching substantially from port-plate to port-plate, the pipe being adapted to receive the blast from a blowing-engine or the like; E, capped 45 bearings projecting in pairs, bracket-like, from the port-plates, and engaging the bustle-pipe; F, the tuyere-noses, in the form of a hollow cylinder having a flared upper extremity, and constructed of fire-clay or other refractory 50 material; G, a tuyere reciprocating air-cylinder.

der, of which there is one for each tuyere; H, a hollow arm reaching from this air-cylinder to trunnions engaging the bearings E and serving as a blast-conduit and as a supporting-arm for the tuyere mechanism, the arm 55 being cast with the cylinder; I, an air-relief pipe arranged in bustle form below the bustle-pipe D; J, a free outlet-valve to this outlet-pipe; K, rigid branch pipes leading from the outlet-pipe I, upward outside the 60 bustle-pipe D, at each tuyere; L, flexible pipes forming upward continuations of the branch pipes K, and leading one to the upper portion of each air-cylinder; M, a swivelled union, with a horizontal axis forming a 65 juncture between each of the branch pipes K and its flexible continuation, these swivels being disposed with their axes, as near as practicable, coincident with the axes of the oscillating tuyere mechanism; N, dotted lines indicating the position of a tuyere, &c., when tipped outward; O, a slot-like port through the wall of the vessel, with its bottom disposed below the horizontal plane occupied by the metal work of the tuyere attachments; P, a 70 perforated block formed of fire-clay or the like, and luted into the port O at proper height and adapted to serve as a cinder-notch; Q, the tapping-hole of the vessel; R, Fig. 3, a hollow T-piece formed at the lower end of each arm 75 H, and provided at each end with cylindrical trunnions supported in the bearings E; S, the piston of the air-cylinder; T, a secondary air-cylinder disposed below and in line with each air-cylinder G, and of less diameter than the 80 cylinder above it; U, the piston of the secondary cylinder, having a large taper bore and united to the piston of the upper cylinder by a large hollow neck; V, a tapered tuyere-shank 85 fitting into the piston U and locked thereto 90 by bayonet-joints and having its lower end threaded; W, a metal tuyere-tube fixed in the tuyere-shank V and engaged detachably by the fire-clay tuyere-nose; X, a ferrule engaged 95 by the flare of the tuyere-nose and the thread of the shank; Y, the tapered lower extremity of the tuyere-tube, the same fitting a taper contraction in the bore of the tuyere-nose; Z, ports in the neck connecting the two air-pistons, the same serving to permit air to pass 100

freely to the interior of the neck; *a*, a valve-seat in the piston-neck; *b*, a valve adapted to engage this seat, and provided with a long stem fitted to slide freely through the piston 5 *S* and through the upper cylinder-head; *c*, a collar adjustable along this stem and supported by the upper cylinder-head; *d*, a central bushing screwed into the piston *S* and serving to close the top of the piston-neck and furnish a bearing and guide for the stemmed valve *b*; *e*, apertures through the piston *S*; *f*, a thumb-screw in the wall of the cylinder *G* at a point just above the piston *S*, when that piston is in its lowest position, and *g* a diagonally-disposed circular flange formed upon the exterior of the cylinder *T* and having a beveled periphery fitting the opening of the port-plate. I have referred to a cylinder, a piston, &c. It should be obvious that there are as many 20 of these devices as there are tuyeres. There may be as many tuyeres as desired; but in Fig. 1 I have shown the vessel as provided with three tuyeres and their pertinent accessories. A single tuyere may be employed, if desired.

When the tuyeres are in working position—that is, with the tuyere-noses projected downward into the vessel, as indicated in Fig. 1—the blast will pass from the bustle pipe through 30 the trunnions and arms into the piston-necks, through the ports *Z*, and thence through the tuyeres. The valve *J* being shut, it is obvious that the air-pressure will be equalized upon each side of the piston *S*, there being no outlet for such air as may have passed through the apertures *e*; hence the gravity of the tuyeres is sufficient to hold them in their working position. If the valve *J* be opened, the air-pressure will be relieved from the upper side 40 of the piston *S*, and the air passing through the apertures *e* will not be sufficient to create a pressure. Consequently the air-pressure acts upon the under side only of the piston *S*, causing this piston to rise and withdraw the tuyere from the metal. As the piston, &c., rises, the seat *a* engages its valve, and the valve then also rises, thus cutting off the blast from the tuyere at any desired point in the rising motion of the tuyere, as determined by the 45 setting of the collar *c*. This automatic cutting off of the blast not only serves to prevent the further blowing of the metal, but also serves to prevent the escape of air from the tuyere when the same has left the metal—an escape which, if unprevented, would materially lessen the pressure under the piston *S* and in the general blast system. It will thus be seen that by the simple opening of the valve *J* the tuyeres may be instantly withdrawn from the 55 metal and the duration of blow thus accurately timed, and that the time of the immersion of the tuyeres is shortened as much as possible.

When the valve *J* is closed, the air-pressure 60 will again equalize itself upon the two sides of the piston *S*, and the tuyere will again descend into the metal, the descent being aug-

mented by the unbalanced pressure of the blast upon the piston *U*.

The cinder-block *P* can be set at any height 70 desired in the slot before being luted, and should be so located in its port that the metal line will not reach the metal-work of the tuyere attachments.

When the tuyere is retracted, the entire tuyere 75 structure may be swung back into the position indicated at *N*, Fig. 1. This leaves the ports of the vessel entirely open, and the interior of the vessel may be inspected through them. As the tuyere structure swings backward the 80 outlet-pipe *L* oscillates upon the swivel *M*. Were the axis of the swivel *M* disposed coincident with the axes of the trunnions the pipe 85 *L* might be rigid. The axes are not, however, coincident, and as a consequence the pipe *L* will be called upon for a slight flexation.

The bustle-pipe *D* is, as before mentioned, formed in segments. The ends of these segments engage the bearings of the port-plates, and are snugly babbited therein in line with 90 the trunnions, which are also babbited in the bearings. When the tuyere device is swung back, the tuyere proper may again be protruded, so that the tuyere noses will be readily accessible for renewal, &c. The thumb-screw 95 *f* may be screwed inward, so as to support the sliding features when the tuyere device is swung backward and the blast-pressure taken off entirely.

By disengaging the bayonet-joint which connects the tuyere-shank with the smaller piston, the tuyere-nose, with its body and shank, may be readily removed and another one substituted; or the ferrule *X* may be unscrewed from the shank, thus permitting the fire-clay 105 tuyere-nose to be slipped off of the tuyere-tube *W*, so that a new one can be substituted. The tuyere-tube furnishes an inner support for the fire-clay tuyere-nose, and the ferrule *X* draws the tuyere-nose snugly against the face of the 110 shank, and at the same time grasps it firmly sidewise, the taper portion *Y* of the tuyere-tube engaging neatly the appropriate portion of the bore of the tuyere-nose, thus giving the tuyere-nose a good support at both its ends, 115 while the tuyere-tube may be fitted very freely within its bore, which is liable to be more or less irregular. The duty of these tuyere-noses is a destructive one, and my device renders replacement of tuyeres a matter of great ease, as 120 well as lessening the destruction, by providing for an instantaneous withdrawal.

The smaller piston, *U*, is either longitudinally fluted or loosely fitted in its cylinder, so that a portion of the blast will waste downward past it and serve in cooling the ferrule *X*, &c., and also serve to forcibly prevent upward splashing of the liquid metal into the tuyere-port and to blow the slag from the tuyere-port.

The flange *g* should seat into the port-plate with sufficient accuracy to fairly and squarely support the tuyere mechanism without imposing improper side strains upon the trun-

nions, and to close the opening in the port-plate fairly tight. This seating may be a simple bevel, as shown in the drawings, or the beveling may be spherical. If accurately-fitting castings are employed, all machine finishing at this joint may be avoided.

5 The axis of the trunnions of the tuyere mechanism is so disposed outwardly that when the tuyere mechanism is in working position 10 the center of gravity of the tuyere mechanism will have passed inward beyond the vertical plane of the trunnion-axis, whereby the tuyere mechanism is maintained in working position without the use of retaining-latchments.

15 It is found if the diagonal tuyere-ports be arranged through a converter-wall which is vertical at the port-point that the lining will present acute and fragile edges at the port-openings. I secure stability at these edges by 20 coning the converter at the port-point, as shown, whereby excessive acuteness is avoided.

25 I have referred to the tube W as being rigidly secured in the shank. While this may be perfectly satisfactory under some conditions, I find that it will be desirable in many cases 30 to have the top separable from the shank, so that the tube may be daubed with clay luting and then inserted into the tuyere-nose, whereby the tube becomes a part of the tuyere-nose rather than of the shank. The tube then serves as a stiffener to prevent the tuyere from being broken by a transverse strain.

35 In order to explain my invention fully, it has been necessary to show and describe much that is not original with me.

The following claims are intended to particularly point out and distinctly claim the parts, improvements, and combinations which are of my invention.

40 Diagonally-arranged tuyeres, tuyeres having a taper fit in the tuyere-ports, tuyeres fitted to revolve or slide through port-margining boxes or plates, tuyeres supported free of contact with their port-walls, shouldered tuyeres 45 fitting in or supported by the port-walls, and tuyeres fitted for universal movement in the ports by means of a globe bearing of oscillation are old. My device is an improvement on such, in that my arrangement of port-plate 50 and flanged tuyere serves in fixing the exact location and projection of the tuyeres independent of any portion of the walls of the port and free therefrom.

55 Inclined tuyere-ports and cinder-notches are old. My device is an improvement over former devices, in that the wall-slot permits the cinder-notch to be readily set at proper height with reference to the metallic tuyere-holding parts disposed in the length of the inclined 60 tuyere-ports.

Injectors of various kinds have been provided with central jets and with annular jets to the rear exterior thereof, such separate jets in all cases being connected with sources of 65 supply of different material, the intention being that the suction produced by one jet shall cause a flow of dissimilar material from the

other jet. Tuyeres have also been devised to simultaneously inject dissimilar matters through a single-blast apparatus. My arrangement of tuyeres with extra blast-outlet 70 is distinguishable from others, in that one blast-jet does not depend upon another for its jetting power. The matter jetted is the same with all the jets, and the extra jet is arranged to 75 keep clear a tuyere and port otherwise disposed to fouling, &c., by slag.

Clay tuyere-noses have been shanked directly into holding-sockets, an arrangement clearly distinguishable from my plan of arming the fragile tuyere-nose with a metallic shank secured to the periphery of the heel of the tuyere. The heels of tuyere-noses have been flared to engage directly the flared tuyere-holder; but such tuyere-noses have not seated 85 endwise against their holders, nor have they been removable forwardly from their holders. Tuyere-noses have had central stiffening-tubes; but the tubes have had a head at the extremity of the tuyere-nose, or have been the sole support for the tuyere-nose, or have been left unsecured to the tuyere-holder. None of the old devices provide for the quick and safe removal of the tuyere-nose outwardly from the holder without the necessity of removing hot keys or 90 nuts, or the like, unless there were employed attaching devices not satisfactorily applicable to tuyere-noses of clay or analogous fragile material.

95 Reciprocating tuyeres combined with screws, pneumatic arm-cranes, chains, racks, and other operating devices are old, as are also tuyere-plugs operated by air-pistons and otherwise. So far as I know I am the first to provide a combination of mechanism by means of which 105 the blast-air is permitted to act directly on the pistonial enlargement of the tuyere and shut itself as the tuyere retreats.

110 In the arrangement of tuyeres it is common to connect a trunnioned pipe articulately to the tuyere, and it has been proposed to secure the tuyere to the hinged roof of a converter. My device presents a distinct improvement, in that the trunnioned arm is connected rigidly to the tuyere, and the wall-work need not be 115 oscillated when the tuyere is withdrawn.

I claim as my invention—

1. The combination of a metallurgical vessel provided with a tuyere-port, a plate having a central opening and secured to the exterior surface of the vessel and forming a margin to the port, and a tuyere fitted to project into and through such port free of contact with the walls thereof and provided with a flange whose periphery seats in said opening. 120

2. The combination of a metallurgical vessel provided with a downwardly-inclined tuyere-port and with a wall-slot, a tuyere-nose of refractory material projecting inwardly through the tuyere-port, free of the walls thereof, metallic tuyere-nose-holding parts disposed within the upper outer portion of said tuyere-port, and a cinder-notch block disposed in said 130 wall-slot.

3. A tuyere having a blast-discharge outlet at its nose and a blast-discharge outlet at a point back of its nose, said second discharge-outlet being arranged to direct its blast along 5 outside the tuyere.
4. The combination of a metallurgical vessel having a tuyere-port and a tuyere projecting into the vessel from the port, and having a central longitudinal blast-passage connecting 10 its inner extremity with a source of air-supply for blast, and having also a blast-outlet at a point backward of its nose connected with the said source of supply of air for blast and arranged to discharge along outside the tuyere 15 and parallel with it.
5. The combination of a metallurgical vessel having a tuyere-port and a tuyere projecting into the vessel from within said port, but free of the walls of the port; and having a central longitudinal blast-passage connecting its 20 inner extremity with a source of air-supply for blast, and having also a blast-outlet within the port and arranged to discharge along the outside of the tuyere within the port and 25 thence into the vessel, and connected with said source of air-supply for blast.
6. The combination of a tuyere-nose of clay or other fragile refractory material, a socketed tuyere-support, and a metallic shank secured to the periphery of the heel of the 30 tuyere-nose and adapted to separably enter and engage the socket of the support, substantially as set forth.
7. The combination of a tuyere-nose of clay or other fragile refractory material, a socketed tuyere-support, and a metallic shank secured to the periphery of the heel of the tuyere-nose and engaging the socket of the support by a bayonet joint connection, substantially as set 35 forth.
8. The combination of a tuyere-nose of clay or other fragile refractory material, a tuyere-support provided with a tapered socket, and a tapered metallic shank secured to the nose, substantially as set forth.
9. The combination of a tuyere-nose of clay or other refractory material, a tuyere-support provided with a tapered socket, and a tapered metallic shank secured to the nose and engaging 40 said socket by a bayonet-connection, substantially as set forth.
10. The combination of a tuyere-nose having an enlarged rear end seating against its holder and a ferrule engaging the front of such enlargement and secured to the holder, substantially as set forth.
11. The combination of a tuyere-nose having at its rear end a flared enlargement and seating endwise against its holder and a ferrule 45 engaging such flared enlargement and secured to the holder, substantially as set forth.
12. The combination of a tuyere-nose having an enlargement at its rear end seating against an exteriorly-threaded holder and a ferrule engaging the enlargement of the tuyere-nose and the thread of the holder, substantially as set forth.
13. The combination of a tuyere-nose having at its rear end a flared enlargement seating against an exteriorly-threaded holder and a ferrule engaging the flared enlargement of the tuyere-nose and the thread of the holder, substantially as set forth. 70
14. The combination of a tuyere-nose secured to its holder at one end and a tube rigidly secured to the holder and projecting into the bore of the tuyere-nose, substantially as set forth. 75
15. The combination of a tuyere-nose secured to its holder at one end and a tube rigidly secured to the holder and projecting into the bore of the tuyere-nose and provided with a tapered extremity engaging a tapered portion of the tuyere-nose, substantially as set forth. 80
16. The combination of a socketed tuyere-support, a tuyere-shank engaging such socket, a tube rigidly secured to the shank, a tuyere-nose encircling the tube and seating endwise against the shank, and a ferrule uniting the tuyere-nose to the shank, substantially as set forth. 85
17. The combination of a socketed tuyere-support, a shank engaging such socket, a tube rigidly secured to the shank and having a tapered extremity, and a tuyere-nose encircling the tube and engaging the tapered extremity thereof, substantially as set forth. 90
18. The combination of a socketed tuyere-support, a shank engaging the same, a tube rigidly secured to the shank and having a tapered extremity, a tuyere-nose encircling the tube and engaging the tapered extremity thereof and provided with a flared enlargement at its rear end, and a ferrule engaging such flared enlargement and the shank, substantially as set forth. 95
19. The combination of a tuyere-support having a tapered socket, a tapered shank engaging the same by a bayonet-joint, a tube rigidly secured to the shank, and a tuyere-nose encircling the tube and coupled to the shank, substantially as set forth. 100
20. The combination of a tuyere, a cylinder arranged coaxially with the tuyere, and a piston in this cylinder connected to the tuyere and adapted to withdraw the tuyere, substantially as set forth. 105
21. The combination of a tuyere, a cylinder having a top outlet controlled by a valve, a piston in the cylinder connected to the tuyere and having perforations or equivalent passages through or past it, and a conduit leading to the under side of the piston, substantially as set forth. 110
22. The combination of a tuyere, a cylinder having a top outlet controlled by a valve, a piston in said cylinder connected to the tuyere and having perforations or equivalent passages through or past it, and a blast-conduit leading to the tuyere and to the under side of said piston, substantially as and for the purpose set forth. 115
23. The combination of a tuyere, two pistons of unequal area attached to the tuyere and

adapted to reciprocate in cylinders, an outlet-pipe at the top of the larger cylinder controlled by a valve, and a conduit leading to the interior faces of the two pistons, substantially as set forth.

24. The combination of a tuyere, two pistons of unequal area attached to the tuyere and adapted to reciprocate in cylinders, an outlet-pipe at the top of the larger cylinder controlled by a valve, and a blast-conduit leading to the tuyere and to the interior faces of the two pistons, substantially as set forth.

25. The combination of two or more tuyeres, a cylinder at each tuyere, outlets connected from the top of each cylinder and controlled by a single valve, and a piston in each cylinder attached to its appropriate tuyere, substantially as set forth.

26. The combination of a metallurgical vessel, a tuyere fitted to reciprocate into and out of the metal in the vessel, and a valve in the blast-passage of the tuyere arranged to be opened and closed by the reciprocation of the tuyere, substantially as and for the purpose set forth.

27. The combination of cylinders G and T, pistons S and U, connected by a hollow neck, port Z through the neck, and the tuyere attached to the pistons, substantially as set forth.

28. The combination of the tuyere provided with a valve-seat in its blast-passage and a valve resting above said valve-seat and adapted to reciprocate with the tuyere after the valve closes, substantially as set forth.

29. The combination of a tuyere fitted to reciprocate and provided with a valve-seat in its blast-passage, a valve for such seat provided with a stem adapted to reciprocate through a support, and an adjustable collar on the stem and engaging the support, substantially as set forth.

30. The combination, with a reciprocating tuyere and its operating-cylinder, of piston S, connected to the tuyere by a hollow neck, valve-seat *a*, stemmed valve *b*, supported by the piston and cylinder-head, and collar *c*, substantially as set forth.

31. The combination, with a reciprocating tuyere and its operating-cylinder, of piston S, connected to the tuyere by a hollow neck, valve-seat *a*, bushing *d*, stemmed valve *b*, and collar *c*, substantially as set forth.

32. The combination, with a reciprocating tuyere and its operating cylinder and piston G S, of pin or screw *f*, substantially as and for the purpose set forth.

33. The combination of a metallurgical vessel, a blast-pipe disposed in bustle form around the vessel, a circular series of reciprocating

tuyeres provided with operating-cylinders arranged above said blast-pipe and connected therewith, an outlet-pipe arranged in bustle form around the vessel and provided with a valve, and branches leading from said outlet-pipe to the operating-cylinders of the tuyeres, substantially as set forth.

34. The combination of a metallurgical vessel, an angularly-disposed tuyere formed separate from the wall-work of said vessel, a rigid arm projecting from the tuyere and provided with horizontal trunnions, and trunnion-bearings secured to the outlet-surface of the vessel.

35. The combination of a plate having an opening to margin a tuyere-port and provided with trunnion-bearings and a tuyere fitted to such opening and having a rigid projecting arm provided with trunnions.

36. The combination of a tuyere provided with an operating-cylinder and mounted on trunnions, an outlet-pipe, K, a swivel, M, 80 thereon, and a pipe, L, leading from the tuyere-cylinder to the swivel, substantially as set forth.

37. The combination of a tuyere provided with an operating-cylinder mounted on trunnions, an outlet-pipe, K, pipe-swivel M thereon, and flexible pipe L, connecting the tuyere-cylinder with the swivel, substantially as set forth.

38. The combination of a metallurgical vessel, a trunnion-bearing secured to the outside 90 of the vessel, a tuyere supported thereby, an outlet-pipe terminating in a swivel whose axis is disposed parallel with but outside the plane of the axis of the tuyere-trunnion, and a flexible pipe reaching from the swivel to the oscillating tuyere structure, substantially as set forth.

39. The combination of a tuyere-supporting structure provided with trunnions and a tuyere fitted to reciprocate therein, substantially as set forth.

40. The combination of a metallurgical vessel, a tuyere-supporting structure provided with trunnions, and a tuyere fitted to reciprocate therein and inclined downward from the 105 outside of the vessel, substantially as set forth.

41. The combination of a tuyere-supporting structure provided with trunnions, a tuyere fitted to reciprocate therein, and a pin or screw adapted to maintain the tuyere in a position 110 of upward protrusion when the tuyere-supporting structure is swung into its backward position, substantially as set forth.
